UNITED STATES PATENT OFFICE.

HIRAM H. SPONENBURG, OF WADSWORTH, ILLINOIS, ASSIGNOR OF ONE-HALF TO EDWARD LAAS, OF OTTUMWA, IOWA.

RAILWAY-RAIL STAY.

No. 816,946.

Specification of Letters Patent.

Patented April 3, 1906.

Application filed September 11, 1905. Serial No. 277,361.

To all whom it may concern:

Be it known that I, HIRAM H. SPONENBURG, a citizen of the United States, and a resident of Wadsworth, in the county of Lake, in the State of Illinois, have invented new and useful Improvements in Railway-Rail Stays, of which the following, taken in connection with the accompanying drawings, is a full, clear, and exact description.

10 This invention relates to the class of rail-stays which are fastened to the rail and abut against the side of the subjacent cross-tie to prevent longitudinal creeping of the rail.

15 The object of the invention is to provide a rail-stay which shall be adjustable to different widths of the bases of the rails to which the stay is to be applied and shall obtain a firm hold on the rail, which hold shall be automatically augmented by the strain exerted on 20 the stay in resisting the creeping of the rail; and to that end the invention consists in the improved construction and combination of the component parts of the rail-stay, as hereinafter set forth.

25 The invention is illustrated in the accompanying drawings, in which—

Figure 1 is a transverse section of a rail equipped with a rail-stay embodying my present invention. Fig. 2 is a plan view of 30 the same. Fig. 3 is a side view. Fig. 4 is a detached plan view of the bar which carries the rail-gripping jaws. Fig. 5 is an inverted plan view of the said bar. Fig. 6 is a plan view of a modification of said bar. Fig. 7 is a transverse section on the line $z-z$ in Fig. 6. Fig. 8 is a detached inverted plan view of the 35 adjustable rail-gripping jaw.

R denotes the rail, and A one of the cross-ties which support said rail.

40 a represents a stout metal bar which extends across the bottom of the rail and abuts against the side of the cross-tie to resist the longitudinal movement of the rail. Said bar is provided on one end with a rigid jaw b, 45 preferably formed integral with the bar and suitably shaped to effectually grip the flange c on one side of the rail. The opposite end of the bar a is provided with a longitudinal slot d' and has adjustably mounted upon it the 50 jaw d, which bears with its overhanging lip onto the top of the adjacent rail-flange c'. The bar a and the jaw b, affixed thereto, are both reinforced by means of ribs e e, formed on the under side of the bar and extending

lengthwise thereof and on the back and top 55 of the jaw b. The jaw d is clamped in its adjusted position by a bolt f, passing through the slot d' and through hole d' in the said jaw and provided with a head g and a nut g' on its opposite ends. The slot d' allows the jaw d 60 to be adjusted to rail-bases of different widths. In order to render the grip of the jaw d more effective, I fulerum the said jaw at its outer end on the bar a, preferably by means of a transverse rib h, projecting from 65 the under side of the jaw and bearing on the bar, as shown in Fig. 1 of the drawings. I prefer to form the said rib on a bar of steel or case-hardened iron, which bar I suitably secure in a groove h' in the under side of the 70 jaw. The inner end or overhanging lip of the said jaw I provide with a hard-metal gripping-plate i, seated in a recess in the under side of said lip and retained therein by clenches j, formed on the lip and engaging 75 the outer edge of the plate, which is formed with sharp-edged ribs j' to cut their way into the top of the rail-flange c' in the operation of tightening the jaw on the bar a. The bolt f, which clamps the jaw d on the bar a, is arranged between the fulcrum h and the rail-gripping lip of the jaw, and thus causes said lip to obtain a secure hold on the rail.

At opposite sides of the slot d' are longitudinal hard-metal plates l l, which are fastened 85 in grooves l' l' and are formed with longitudinal ribs n n on their tops, said ribs engaging the under side of the rail-flange, and thus preventing the rail from slipping longitudinally on the bar a, which abuts against the side of 90 the cross-tie.

In order to cause the jaws to automatically augment their grips on the rail in resisting the creeping thereof, I form one end of the bar, preferably the slotted end, with a lateral 95 extension o and with a depending flange p on the end of said extension. The said flange constitutes the abutment by which the bar a bears on the side of the cross-tie. The extension o causes the opposite end of the bar a 100 to be disposed normally out of contact with the cross-tie, as shown in Fig. 2 of the drawings. The bar a is thus allowed to be forced into an oblique position by severe longitudinal strain of the rail. Said movement of the 105 bar causes the jaws to more effectually grip the rail-flanges.

The bar a may be formed with an addi-

tional lateral extension o' opposite the extension o , as shown in Figs. 6 and 7 of the drawings. The bar thus constructed allows the rail-stay to be applied to either side of the track. The flanges p are braced by means of a web p' , extending across the under side of the bar a and its lateral extensions o o' , as shown in Fig. 7 of the drawings.

What I claim as my invention is—

1. The improved rail-stay consisting of a bar extending across the bottom of the rail and provided on one end with a rail-gripping jaw, a jaw mounted adjustably on the opposite end of the bar, means formed separate from the bar for clamping the jaw in its position a lateral extension on one end of the bar and a tie abutment on said extension. 65
2. A rail-stay consisting of a bar extending across the bottom of the rail and provided on one end with a rail-gripping jaw, and on the opposite end with ribbed rail-bearings, a jaw disposed over said rail-bearings, and means for adjustably clamping said jaw to the bar. 70
3. A rail-stay consisting of a bar extending across the bottom of the rail and formed at one end with a rail-gripping jaw and at the opposite end with grooves in its top, hard-metal plates seated in said grooves and provided with ribs on their tops, a jaw disposed over the said plates, and means for adjustably clamping said jaw to the bar. 75
4. A rail-stay consisting of a bar extending across the bottom of the rail and formed at one end with a rail-gripping jaw, and at the opposite end with a longitudinal slot, a jaw mounted adjustably on said slotted end of the bar, and a bolt passing through the said slot and clamping the jaw in its adjusted position. 80
5. A rail-stay consisting of a bar extending across the bottom of the rail and formed at one end with a rail-gripping jaw, a longitudinal slot in the opposite end of the bar, ribbed rail-bearings on the bar at opposite sides of the slot, a jaw mounted on the slotted end of the bar, and a bolt passing through the slot and clamping the jaw in its adjusted position. 85
6. A rail-stay consisting of a bar extending across the bottom of the rail and formed at one end with a rail-gripping jaw, a longitudinal slot in the opposite end of the bar, grooves in the bar at opposite sides of the slot, rail-bearing plates seated in said grooves, a jaw mounted adjustably on the slotted end of the bar, and a bolt passing through the aforesaid slot and clamping the jaw in its adjusted position. 90
7. A rail-stay consisting of a bar extending across the bottom of the rail and formed at one end with a rail-gripping jaw, reinforcing ribs extending around the back and onto the top of said jaw, a longitudinal slot in the opposite end of the bar, grooves in the bar at opposite sides of said slot, rail-bearing plates seated in said grooves, a jaw mounted adjustably on the slotted end of the bar, and a bolt passing through the aforesaid slot and clamping the jaw in its adjusted position. 95
8. A rail-stay consisting of a bar extending across the bottom of the rail and formed at one end with a rail-gripping jaw and at the opposite end with a longitudinal slot, a lateral extension on the slotted portion of the bar, a tie abutment depending from said extension, rail-bearings disposed at opposite sides of the slot and provided with rail-gripping ribs disposed parallel with the bar, a jaw mounted adjustably on the slotted portion of the bar, and a bolt passing through the aforesaid slot and clamping the jaw in its adjusted position. 100
9. A rail-stay consisting of a bar extending across the bottom of the rail and formed at one end with a rail-gripping jaw and at the opposite end with a longitudinal slot, longitudinal grooves in the bar at opposite sides of the slot, a lateral extension on the slotted portion of the bar, a tie abutment depending from said extension, plates seated in the aforesaid grooves and formed with rail-gripping ribs disposed parallel with the bar, a jaw mounted adjustably on the bar, and a bolt passing through the aforesaid slot and clamping the jaw in its adjusted position. 105
10. In combination with a rail and a bar disposed at the base of said rail, a jaw fulcrumed at one end on said bar and bearing at its opposite end upon the top of the flange of the rail, and means depressing said jaw onto its said bearings. 110
11. A rail-stay consisting of a bar extending across the bottom of the rail and formed at one end with a rail-gripping jaw and at the opposite end with a longitudinal slot, grooves in the bar at opposite sides of the slot, rail-bearing plates seated in said grooves and provided on their tops with ribs disposed parallel with the bar, a lateral extension on the slotted portion of the bar, a tie abutment depending from said extension, a jaw provided on the under side of its outer portion with a transverse bearing-rib, and on the under side of its inner overhanging portion with a ribbed hard-metal plate, and a bolt passing through the aforesaid slot and clamping the jaw in its adjusted position as set forth and shown. 115
12. A rail-stay consisting of a bar extending across the bottom of the rail and provided at one end with a jaw adapted to grip one of the rail-flanges, a jaw mounted adjustably on the opposite end of the bar for gripping the other rail-flange and provided with a transverse rib on its under side by which it is fulcrumed on the bar, and means for clamping the latter jaw in its position as set forth. 120
13. A rail-stay consisting of a bar extend-

ing across the bottom of the rail and provided at one end with a jaw adapted to grip one of the rail-flanges, a jaw mounted longitudinally adjustable on the opposite end of the bar for gripping the other rail-flange and provided with a transverse groove in its under side, a hard-metal rib secured in said groove

and affording a fulcrum for the jaw on said bar, and means for clamping the latter jaw in its position as set forth.
